[57] CLAIM

The ornamental design for a shower filter housing, as shown and described.

DESCRIPTION

FIG. 1 is a perspective view of my new shower filter housing design;

FIG. 2 is a front elevational view of my new design as shown in FIG. 1, with the opposite or rear view, being the mirror image thereof;

FIG. 3 is a top view of my new design as shown in FIG. 1; FIG. 4 is a bottom view of my new design as shown in FIG. 1;

FIG. 5 is a perspective view of my new shower filter housing design, as shown in FIG. 1, with the centrally located indented or label carrying portion thereof removed; and, FIG. 6 is a further perspective view of my new shower filter housing design, as shown in FIG. 5, with the top surface thereof being identical with the bottom surface.
